UNITED STATES PATENT OFFICE.

GEORGE OTIS HARWELL, OF OROSI, CALIFORNIA, ASSIGNOR OF ONE-THIRD TO EUGENE L. HARWELL AND ONE-THIRD TO ERNEST M. HARWELL, OF CLOVIS, CALIFORNIA.

RADIATOR ATTACHMENT FOR INTERNAL-COMBUSTION ENGINES.

1,251,227.

Specification of Letters Patent.

Patented Dec. 25, 1917.

Application filed August 2, 1916. Serial No. 112,782.

To all whom it may concern:

Be it known that I, GEORGE OTIS HARWELL, a citizen of the United States, residing at Orosi, in the county of Tulare and State of California, have invented certain new and useful Improvements in Radiator Attachments for Internal-Combustion Engines, of which the following is a specification, reference being had to the accompanying drawings.

This invention comprehends certain new and useful improvements in automobile appliances or accessories, and relates particularly to a device designed to be operatively connected to the radiator of an automobile, motor vehicle or the like, so as to constitute a reserve supply reservoir for water for the radiator and to condense the steam which is generated within the latter.

The invention has for its primary object a simple, durable, and efficient construction of device of this character which may be very cheaply made and easily installed, or applied in operative position without the necessity of special tools and with very little trouble or work and without altering the construction or arrangement of parts of the motor and radiator, and the invention also aims to generally improve devices of this class so as to render them more useful and commercially desirable.

With these and other objects in view, as will more fully appear as the description proceeds, the invention consists in certain constructions, arrangements and combinations of the parts that I shall hereinafter more fully describe and claim.

For a full understanding of the invention, reference is to be had to the following description and accompanying drawing, in which—

Figure 1 is a side elevation of my device partly broken out, the device being shown in applied position.

Fig. 2 is a side elevation at right-angles to the position of the device as shown in Fig. 1, and

Fig. 3 is a top plan view.

Corresponding and like parts are referred to in the following description and accompanying drawing by like reference characters.

Referring to the drawing, the numeral 1 designates the radiator of an automobile, 55 and 2 the usual overflow pipe thereof, these

parts being of any desired construction or design according to the make of automobile to which my invention is applied.

In carrying out my invention, I provide a preferably cylindrical casing 3 formed of any desired substance or material and of any desired size and shape, said casing constituting a water reservoir and being designed to be held in position in any desired way as, for example, by means of a split band 4, which is provided at one point with an apertured ear 5, through which one of the head bolts of the engine or motor may extend. The casing 3 is provided in its top with a fill opening that is normally closed by means of a cap 6, the cap being provided with any desired number of perforations 7, for the escape of steam, if necessary.

The casing 3 is provided at or near its bottom with a downwardly inclined nipple 8 which preferably extends forwardly in the applied position of the device, and which is designed to have secured thereto one end of a flexible conduit or rubber hose 9. The other end of this conduit is adapted to be slipped upon the lowermost rearwardly and downwardly projecting end 10 of the overflow pipe 2, as clearly illustrated in the drawing.

Preferably, the casing 3 is supported immediately behind the radiator 1 so that the fan of the motor will act thereon to assist in keeping the contents of the casing cool, and to further assist in maintaining the water cool within the casing, the casing is provided with a passage 11 extending horizontally therethrough and open throughout its length to the exterior atmosphere so that air may pass freely through this passage in an evident manner.

From the foregoing description in connection with the accompanying drawing, the operation of my improved radiator attachment will be apparent. In the practical use of the device, the band 4 is clamped around the reservoir 3, and the band secured in proper position by means of one of the head bolts extending through the apertured ear 5, and the conduit 9 is connected to the nipple 8 and lowermost end 10 of the radiator overflow pipe 2.

Assuming that there is a certain amount of water in the radiator, and a certain amount of water in the reservoir tank 3, then it is obvious that the water level in the 110

reservoir tank 3 and the water level in the overflow pipe 2 will be the same. Now upon starting the motor, the water in the radiator becomes heated and if sufficiently heated, 5 steam will be generated. The expansion of the steam and the water due to the heating will drive whatever air there is in the upper portion of the radiator over into the overflow pipe and out through the overflow pipe, 10 that is, through the liquid therein into the reservoir tank 3 and out through the perforations 7 in the cap of the reservoir tank. When this air has escaped, the steam which is within the upper portion of the radiator 15 and within the upper portion of the reservoir pipe, would attempt to force its way through the overflow pipe and into the reservoir tank, and this steam coming in contact with the relatively cold water in the 20 pipe 2 and in the reservoir tank would condense. So long as the steam continues to be generated, it will be forced over into the reservoir tank in the manner described, but when the car is stopped or when it is run 25 at a lower speed, the heating effect would be less, the generation of the steam would cease, the water would cease boiling and subside which would leave, if not a complete vacuum in the upper portion of the radiator, 30 at least a partial vacuum. There being a partial vacuum on one side and the pressure of air on the top of the water in the tank 3, it will be obvious that water from the reservoir tank will immediately flow from 35 the reservoir tank through the pipes 9 and 2 into the radiator and to an extent which will fill the radiator.

When again the car is run at a high speed and the water commences to boil and steam

is generated, the operation above stated is 40 repeated and when the car is slowed down or stopped, the water will again pass from the reservoir tank into the radiator. Now it is to be understood that the radiator cap is closed tightly so that no air can get into 45 the radiator through said cap. The steam does not escape but becomes condensed within the tank and thus prevents loss of water and permits the filling of the radiator from the reservoir supply while running. 50

While the accompanying drawing illustrates what I believe to be the preferred embodiment of my invention, it is to be understood that the invention is not limited thereto, but that various changes may be 55 made in the construction, arrangements and proportions of the parts without departing from the scope of the invention as defined in the appended claim. 60

What is claimed, is:

In a motor vehicle having a radiator and a fan, the radiator being provided with an overflow pipe extending from its upper end, a water reservoir mounted immediately behind the fan and having a pipe connection to the lower end of the overflow pipe and having an air inlet in its upper end, said reservoir having an open-ended air pipe extending horizontally through the reservoir directly behind the fan and in a plane at 70 right angles to the plane of rotation of the fan. 65

In testimony whereof I hereunto affix my signature in the presence of two witnesses.

GEORGE OTIS HARWELL.
